UNITED STATES PATENT OFFICE.

NATHAN J. SIMONDS, OF WOBURN, MASSACHUSETTS, ASSIGNOR TO THE TRIUMPH BOTTLE WASHING MACHINE COMPANY, OF SACO, MAINE.

MACHINE FOR WASHING BOTTLES.

SPECIFICATION forming part of Letters Patent No. 373,315, dated November 15, 1887.

Application filed November 3, 1886. Serial No. 217,865. (No model.)

To all whom it may concern:

Be it known that I, NATHAN J. SIMONDS, of Woburn, county of Middlesex, State of Massachusetts, have invented certain new and useful Improvements in Machines for Washing Bottles and like Vessels, of which the following is a specification, reference being had to the drawings accompanying and forming a part hereof, in which—

10 Figure 1 is a vertical section through part of the drum of the machine, showing my improved method of mounting the cradles which receive the necks of the bottles, so that bottles of various lengths may be accommodated, and showing, also, the relative positions of the brushes and rinsing-jets. Fig. 2 is a view of the plates which retain the bottles in position after they are inserted in the drum. Fig. 3 is a transverse section showing some bottles 20 fully inserted in the pockets which receive them and others partially projected from the pockets.

A machine for washing bottles and other vessels consisting of a drum mounted in a tank 25 containing water or other liquid in such manner as to subject about one-half of the drum at a time to immersion in the liquid of the tank, the said drum being provided with pockets or receptacles for holding the bottles while they 30 are being carried through the tank by the rotation of the drum and subjected to the action of revolving brushes and jets of rinsing-water by the action of automatic mechanism mounted within the drum-cylinder, is already 35 well known, and is fully set forth in British Letters Patent No. 16,426 of the year 1884, granted to William Whitfield Horner, as also in a patent to said Horner in the United States, December 7, 1886, No. 354,061, the application for which was filed October 24, 1885, 40 Serial No. 180,802.

My present invention is an improvement in the machine shown in said application of Horner, and has for its object to enable a machine 45 such as he describes to be so constructed as to accommodate bottles of various sizes, which machines of this kind have not hitherto been capable of doing, so far as known to me.

In the drawings hereto attached I have not

deemed it necessary to illustrate fully the entire machine, but only such parts thereof as I deem essential to a full understanding of my present improvement.

I will describe my improvement, using like letters of reference to indicate like parts throughout the drawings.

A represents a section or portion of one of the ends of the drum of Horner's machine. Between the heads or ends of the drum are placed transverse pieces, which form a rack to receive and support the bottles E. The outer series of transverse pieces are provided with apertures somewhat larger in diameter than the diameter of the bottles which they are to receive, while the inner transverse pieces, B, form rests for the pockets a, which receive the necks of the bottles. These pockets a have their cylindrical walls cut away at one part, as shown at h, to accommodate any wire fastening or stopper which may be permanently secured to the bottle. The pockets a are secured to the transverse piece B, and inside each pocket is provided a spiral spring, c, on which rests a thimble or cradle, b, which receives directly the top and neck of the bottle. The cradles are shaped as shown, with a recess into which the top of the bottle is placed, and which acts to hold the bottle in line with the aperture through the cradle and through the transverse piece B, which permits the brush f to pass into the bottle, as also the rinsing-jets g. It is desirable that the bottom of the bottle be at a given point in the drum, whether the bottle be large or small, while being subjected to the operation of the brush, because the brush moves a given distance in brushing a bottle, and it is desirable it should go to the bottom of the bottle. The bottoms of the bottles are therefore allowed to rest under hoods or retaining-plates d, against which they are held by the pressure of the spiral springs c, so that if the bottle be long the spiral spring c will be fully compressed, as shown, while if it be short the spring will be expanded.

In inserting a bottle it is placed top foremost in the pocket, care being taken, if there be a patent stopper on the bottle, that the stopping device pass into the slot h in the

5 pocket, and the bottle is pressed down into the pocket against the force of spring *c* until the bottom is sufficiently within the pocket to be pressed under the retaining-plate *d*. For 10 5 bottles having round bottoms the shape of the retaining plate or hood *d* may require to be slightly changed from the form shown, which is adapted for flat-bottomed bottles, such as are ordinarily used. Such a change, however, 15 will be obvious to those using the machine, and may be readily made when desired. If the retaining-strip *H* be used, the plates or hoods *d* may be dispensed with altogether; but I prefer to use the said plates or hoods, as 20 well as the retaining-strips *H*, in connection with the spring-supported cradles *b*. The strip *H* is secured to cross-pieces *L* in the tank in front of and behind the drum and passes 25 under the drum close to its periphery. A strip is employed for each line of bottles, and the ends of the strips where the bottles first come in contact with them are curved outwardly, as shown at *K*, Fig. 1. As the drum revolves, the projecting bottles strike the outwardly-curved ends *K* of the strips and are forced inwardly into position in the drum, their bottoms sliding on the strips. In this 30 position they are carried through the tank, the strips serving to hold them in position and prevent their dropping down into the tank. 35 *F*, Fig. 1, represents a concave cover, made, preferably, of tin or sheet metal and supported on uprights from the tank. The object of this cover is to receive the jet of rinsing-water in case any of the pockets should be empty; otherwise this water would be thrown out into the room if, by accident or otherwise, there was not a bottle in each pocket.

What I claim is—

40 1. In a bottle-washing machine, the combination, with a rotary bottle-holding drum, of

a series of spring-supported cradles arranged in the interior portion of the said drum and provided with apertures to permit of the passage of the brushes and rinsing-jets to the interiors of the bottles, substantially as set forth. 45

2. In a bottle-washing machine, the combination, with a rotary bottle-holding drum, of a series of spring-supported cradles, *b*, arranged in the interior portion of the said drum and provided with central apertures to permit of the passage of the brushes and rinsing-jets to the interiors of the bottles, and the retaining-plates *d*, co-operating with the said cradles to hold the bottles in the drum, substantially as set forth. 50 55

3. In a bottle-washing machine having a revolving drum, the combination, with said drum, of the pockets *a*, having slots *h* in their walls and containing cradles *b* and their supporting-springs, for the purposes and substantially as set forth. 60

4. In a bottle-washing machine, the combination, as a whole, of the revolving drum, pockets *a*, secured within the same and containing the spring-supported cradles *b*, and the retaining-plates *d*, substantially as shown and described. 65

5. In a bottle-washing machine, the combination, with a rotary bottle-holding drum, of the spring-supported cradles *b*, arranged in the interior portion of the said drum and provided with central apertures to permit of the passage of the brushes and rinsing-jets to the interiors of the bottles, and devices, substantially as described, co-operating with the said cradles for retaining the bottles in the drum, as set forth. 70 75

NATHAN J. SIMONDS.
